PUMP POWER.

APPLICATION FILED OCT. 31, 1906.

3 SHEETS—SHEET 3.

UNITED STATES PATENT OFFICE.

HERBERT H. ICE, OF MONTPELIER, INDIANA.

PUMP POWER.

No. 859,451.

Specification of Letters Patent.

Patented July 9, 1907.

Application filed October 31, 1906. Serial No. 341,429.

To all whom it may concern:

Be it known that I, HERBERT H. ICE, a citizen of the United States, residing at Montpelier, in the county of Blackford and State of Indiana, have invented new 5 and useful Improvements in Pump Power, of which the following is a specification.

This invention is a power mechanism particularly adapted for operating oil well and other pumps.

The object of the invention is to provide a band 10 wheel power having several motions, as compared to the ordinary power having only a single motion.

A further object of the invention is to provide improved means for lubricating the bearing parts or surfaces of the power, so as to avoid friction, wear and noise.

15 The power herein disclosed has two different motions transmitted from one motion of the band wheel. This is advantageous in the practical operation of such devices in oil fields, because wells are of different kinds and can be operated by different strokes. Thus in a field having several large salt-water wells and other head wells, the latter can usually be pumped off in three or four hours, whereas the former would require twelve hours or more. With this power the salt wells could be connected to the double or frequent motion 20 wheel and the head wells to the single motion, thereby decreasing the time the power would have to operate, and avoiding the use of separate gas or steam engines for pumping the salt wells. The power has the further advantage that the bearings are all very large, making 25 it almost impossible to wear out, and the power sets very close to the ground and no over braces or timbers are necessary.

Other advantages of construction will be apparent from the following description and the accompanying 30 drawings.

In the drawings, Figure 1 is a vertical central section of the power. Fig. 2 is a top plan view thereof. Fig. 3 is a section on the line 3—3 of Fig. 1. Fig. 4 is a top plan view of the sliding block shown in Fig. 3. 40 Fig. 5 is a top plan view of one of the sliding blocks of the trammel gear.

In the drawings, 6 indicate a pair of parallel longitudinal sills and 7 a pair of cross sills secured thereto in any suitable manner. The working parts of the apparatus are supported mainly upon the cross sills 7. The bed plate or casting 8 rests upon and is bolted to the sills and has at the center an annular well or groove formed by inner and outer circular walls 9 and 10, cast integral with the bed plate. The inner wall of the 45 groove is preferably tapered or frusto-conical, as shown, and provided with a top part or plate 11 over the central recess.

Mounted upon the bed plate is the central or hub casting 12 of the belt wheel. This casting has a raised part 50 or crown 12^a at the center, within which is a depending tapered rib 13 which fits within the groove in the bed

plate. Bearing balls 14 are placed between the lower edge of the rib and the bottom of the groove, and the upwardly projecting edge of the circular wall 10 projects into the annular space between the rib and the 60 sides of the crown. From the crown the hub plate or casting extends outwardly and horizontally, and is bolted to the arm 15 to which the rim 16 of the main horizontal belt wheel is attached. This construction gives a very wide bearing between the bed plate and the hub 65 plate. Furthermore, the parts are connected by a central bolt 17 which serves to prevent lift of the upper plate. This bolt has a cup head located in a recess 18 on the under side of a trammel plate 19 to be hereinafter described.

70 The hub plate 12 has formed on the upper surface thereof an eccentric groove 19^a within which fits the rib 20 on the under side of the eccentric ring 21. The ring is held down in place by clips 22, and is provided with a plurality of holes around the edge at which may 75 be attached a plurality of well connections 23, the number of these being varied according to the number of wells to be operated. The eccentric gives the normal motion or stroke. It is obvious that at each revolution of the belt wheel the eccentric will be actuated accordingly.

75 To produce a double or faster stroke I provide a trammel gear which is also operated by the belt wheel. This trammel gear consists of a trammel plate 19 having dove-tailed grooves 24 at a right angle. The plate is 80 bolted as at 25 to the crown of the hub casting, and rotates therewith. The blocks 26 slide in the groove, and these blocks have, in the bottoms thereof, oil recesses 27. Each block also has, at the top, a circular rib 28 which fits in an annular groove 29 formed in the 85 under side of the upper trammel disk or plate 30, and the blocks are also formed with central bolts 31 which receive nuts 32 to hold the upper plate to the blocks. The bolts pass through undercut recesses 33. The upper plate 30 is provided around its edges with a series of 90 connections 34 for attachment of the ropes which extend to the wells. A connecting rod 35 extends from one end of the trammel disk 30 to connection with a pivot block 36 which turns in an under-cut recess 37 in a bearing piece 38 which is slidable in a guide-way 39 95 in the top of a standard 40 mounted on the mud sills 6. The connecting rod 35 is extended for connection to a power pump arm, as indicated at 41. The wrist pin or bolt 42, which connects the rod to the block 36, in connection with the slide, permit and guide the movement 100 of the parts incident to the operation of the trammel gear.

105 All the bearings described will be found to run in oil. Thus the groove in which the rib 13 fits is filled with oil, likewise the eccentric groove 19^a and the wrist block 110 groove 39. The trammel blocks 26 form cups at the top which may be filled with oil, and oil is placed and held

within the trammel grooves 24. All the contacting movable parts are thereby thoroughly lubricated and an easy and noiseless action is assured. Two different movements are obtained without the use of toothed gears, the single movement being available from the eccentric and the double movement from the trammel gear. Therefore the well connections may be attached to either, according to the nature of the well to be pumped. Power is applied to the belt well from the engine provided, in the customary manner.

I claim:

1. In a power mechanism, the combination of a frame, a base plate mounted thereon and having an annular groove the walls of which project above the plate, a belt wheel having a raised crown into which the upper ends of said walls extend and a rib extending downwardly from the top of the crown into the groove, and motion-converting devices operatively connected to the wheel.
- 15 2. In a power mechanism, in combination, a belt wheel

having a raised crown at the center and a dropped body 20 around the same, and ring flanges projecting upwardly from said body around said crown, motion-converting devices mounted on the crown and extending outwardly therefrom over the body, and an eccentric ring located between the body and said outwardly extending devices and 25 engaging the flanges.

3. In a power mechanism, in combination, a belt wheel, a trammel gear mounted thereon comprising a lower plate secured to the wheel and having crossed slots, blocks slideable in said slots and having raised circular rims, and an 30 upper plate secured to the blocks and having circular grooves on its under side, into which the rims extend, and also having a connecting rod extending outwardly from the upper plate, and a guide for the outer end of the rod.

In testimony whereof I have signed my name to this 35 specification in the presence of two subscribing witnesses.

HERBERT H. ICE.
